of Oct 2003

UNITED STATES PATENT OFFICE.

ANDREW HUNTER, OF SOLANO COUNTY, CALIFORNIA.

IMPROVEMENT IN GRAIN-SEPARATORS.

Specification forming part of Letters Patent No. 40,340, dated October 20, 1863.

To all whom it may concern:

Be it known that I, ANDREW HUNTER, of the county of Solano, State of California, have invented new and useful Improvements in the Grain-Separators formerly invented by me; and I do hereby declare that the following is a full, clear, and exact description of the construction and operation of the same, reference being had to the annexed drawings, making a part of this specification, in which—

Figure 1 represents a perspective view of said grain-separator. Fig. 2 represents a longitudinal vertical section through the same. Fig. 3 represents a detached view, hereinafter to be referred to.

To enable others skilled in the art to make and use my invention, I will proceed to describe its construction and operation.

A represents the frame of the machine, to which the inclined vibrating shoes B are hung by means of the pivoted hangers C D. The shoes are provided with screens E F G H I K, which are arranged as represented in Fig. 2, causing the larger grain to pass over the screens and over the lower edge of them to the succeeding screens, while the smaller grain, chaff, and seed pass through said screens. The shoes B are operated by means of pitmen t, which are secured to cranks s and to the heads L of the hangers D, and the length of the vibrations of said shoes may be adjusted by setting the heads L higher or lower on said hangers, they being provided for said purpose with holes a.

B' represents another pair of shoes, which are secured to the hangers D, and which are supported by the hinged braces x. They are thus simultaneously vibrated with the shoes B by the action of the crank-shaft and pitmen t, and are inclined in a direction opposite to that of the shoes B, and are provided with screens M for the separation of the smaller grain from seed and chaff. The two crank-shafts s on the crank-shaft u stand under different angles, thus vibrating the two sets of screens alternately and relieving the machine of the jarring motion which results from the action of a single crank motion.

The operation of the machine is as follows: Motion being given to the shaft u, the shoes B and B' are vibrated alternately. The grain to be separated passes from the hopper N to the screen E, the larger grain passing over said screen and over the lower edge down and

over the unperforated parts of the succeeding screens F G H I K and eventually drop on the plate b, whence it passes into the hopper O. The grain, which is of the size of the holes in the above-stated screens passes successively through the screens E F G H I K, passes eventually down to the solid plate P, down said plate and through the aperture d, down upon the screen M, on which the second separation takes place, the grain passing over it and downward. The seed and chaff pass through the screen M and down the solid plate Q. The lower end of the shoes B', together with the part of the frame, are represented in a perspective view at Fig. 3. It will be seen on said figure that oblique strips R are secured to the top of the screens M, and other strips, T, are secured in a reversed position between plate Q and screen M, so as to fill up the entire space between them. When the grain passes down screens M, the strips R guide it so as to drop it into the hopper U, while the smaller seed and chaff, which pass down the plates Q, are guided by the strips T so as to drop into the boxes V, and thus by this arrangement I am enabled to obtain a treble separation of grain, and if the mixture of the grain is such as to require a still further separation an additional screen, with inclined guide pieces or strips, may be used.

Having thus fully described the nature of my invention, what I claim herein as new, and desire to secure by Letters Patent, is—

1. The arrangement of the screens E F G H I K with the plate P, for the purpose of more thoroughly separating the grain to be cleaned from grain of larger size, substantially in the manner and for the purpose described.
2. Affixing to the lower shoes the strips R and similar strips, T, in a reversed position on the bottom of the shoe under the screen M, for the purpose of guiding the grain into the hopper U and chaff or small seed into the hopper V.
3. The arrangement in grain-cleaning machines of trays or shoes in two or more sets, in combination with the reversed cranks and connecting rods, in the manner and for the purposes set forth.

ANDREW HUNTER.
